UNITED STATES PATENT OFFICE.

EDWARD A. ALLEN, OF PORTLAND, MAINE.

APPARATUS FOR ELECTROLYSIS.

1,407,313.

Specification of Letters Patent. Patented Feb. 21, 1922.

Application filed February 15, 1919, Serial No. 277,175. Renewed October 21, 1921. Serial No. 509,400.

To all whom it may concern:

Be it known that I, EDWARD A. ALLEN, a citizen of the United States, residing at Portland, in the county of Cumberland and 5 State of Maine, have invented new and useful Improvements in Apparatus for Electrolysis, of which the following is a specification.

The present invention is concerned with 10 apparatus for decomposing compounds by electrolysis and obtaining desired elements or derivatives of such compounds, or both elements and derivatives thereof; and it is embodied in an electrolytic cell, and in 15 groups or batteries of such cells with connections between them and with a source of electrical energy. I can best set forth the purposes and characteristics of the invention by description and explanation of 20 the special embodiment of such invention which is illustrated in the drawings furnished herewith as part of this specification.

In the drawings here referred to, Figure 1 is a plan view of a unitary collection of 25 cells and of the current conducting connections between such unit and adjacent units and the source of electric current. Figure 2 is an end elevation of the same unit collection. Figure 3 is a cross section on line 30 3—3 of Figure 1. Figure 4 is a longitudinal section of the same on line 4—4 of Figure 1. Figure 5 is a perspective view of a fragment of one of the associated anode guides. Figure 6 is a perspective view of one of 35 the clamp plates or grids forming a part of the cell structure. Figure 7 is a perspective view of the parts of one of the cathode elements prior to the final assembly thereof. Figure 8 is a perspective view of one 40 of the clips used for making connection between an anode and a conductor. Figures 9 and 10 are elevations as seen from directions at right angles to one another of the top of the cell unit, showing a modified form of 45 electrical connection for the same purpose.

The same reference characters indicate the same parts in all the figures.

The unit which I am about to describe contains in one structure a plurality of cells. 50 So far as the basic idea of the invention is concerned, each unit may contain a single cell, or it may contain any number from one up to the limits imposed by considerations of operating efficiency, convenience of handling, and cost of manufacture, installation

and maintenance. I have shown for illustration the form which according to my present ideas combines the greatest number of advantages, and consists of four cells, having their individual anodes and cathodes 60 assembled in one unit structure.

This unit construction comprises a single box or case 11, which I call the cathode chamber, cathodes 12 contained in this chamber, an anode chamber 13, and anodes 14 65 passing through the anode chamber into the cathode chamber. The cathode chamber is a fluid tight box preferably made of cast iron, as that material combines obvious advantages in the mode of making the box and 70 in its finished character, although so far as my claim to protection is concerned I am not restricted as to the material of this part, or as to the mode of making it, but may use any material fashioned in any manner which 75 may be possible to produce a box having the necessary strength and fluid-holding qualities.

The anode chamber here illustrated consists of slabs 15 and 16 forming side walls, 80 slabs 17 and 18 providing the end walls, a cover slab 19 having openings to admit the anodes, cross bars 20 mortised at their ends into the side walls, top and bottom clamp plates 21 and 22 having lugs 23, and tie rods 85 24 with clamp nuts 25 on their ends and engaged with said lugs. The slabs 15, 16, 17, 18, and 19, and the bars 20 are preferably made of slate, as that is a material having insulating qualities, sufficient strength and rigidity 90 for the purpose, and capable of being shaped and finished so as to make tight joints between the contiguous surfaces of the several parts. I would observe, however, that I do not limit my protection to the use of slate 95 for these parts, but include within the scope of such protection, except as otherwise indicated by the express language of the claims, any material and any manner of construction for the anode chamber which may be 100 utilized in such a construction as that described and enables the anodes to be insulated from the cathodes.

The clamp plates are grid-like metallic structures preferably made of cast iron, al- 105 though they may be made of other materials, and by other methods than casting, possessing a rectangular frame, which registers with the side and end walls of the anode chamber, and crossbars 26 which are regu- 110

larly spaced to leave a number of wide openings 27, as shown best by the representation of the plate 22 in Figure 6.

The cathodes are tubular structures of dimensions and cross sectional outline adapting them to fit freely in and pass through the openings 27 of the lower clamp plate. They have lips or flanges 28, 28 and 29, 29 on their upper ends adapted to overlie and rest upon the bottom plate around the rims of the several openings 27. These cathode members are necessarily of conducting material, preferably soft iron, and they are perforated to permit flow of electrolyte.

15 A preferred construction of cathode is shown in Figure 7, being made of two parts 12^a and 12^b, each being a blank cut from a thin sheet of metal with the ends bent up at right angles. Each of these parts has on one 20 edge of its wide central portion an out turned flange 28, and one of them has on the adjacent edges of its turned up ends the flanges 29 previously referred to. The up-turned ends or wings of one of the parts are 25 spaced just enough wider apart than the wings of the other member to embrace such wings between them, whereby the two parts may be placed together so as to make in effect a rectangular tube having a substantially continuous lip at one end, and having the narrower side walls of double thickness. This, however, is only one of the ways in which the cathode may be made, and while I claim the characteristics thus made 30 as part of my invention, I do not limit the protection here sought exclusively thereto. Any construction is within the protection here sought which provides a substantially tubular cathode, whatever may be its outline 35 in cross section, which is adapted to be supported in substantially the manner herein-after described, and has the other characteristics pointed out in the claims. The perforations previously mentioned are indicated at 30 in Figure 7. It is to be understood that substantially the entire walls of the cathode are thus perforated, although I have not attempted to show all the perforations.

40 The tubular cathodes are lined with sheets 31 of insulating material which is sufficiently porous or pervious to the electrolyte to permit flow of the latter to the perforations in the walls of the cathode. Asbestos paper is 45 preferred as the material for this purpose, although I may use any other material having the requisite qualities. When the diaphragms or lining sheets last described are of the material named, or other flexible material, their upper edges are bent over the flanges 28 and 29 of the cathode so as to overlie the same and provide compressible packings between the same and the walls of the anode chamber. The lower ends of the 50 cathode tubes are closed by bottoms 32 of in-

sulating material, preferably blocks of wood, which are fitted to the walls of the cathodes and hold the lower ends of the aforesaid linings or diaphragms in place, also making tight enough joints with such walls to compel substantially all of the electrolyte which flows through the cell to pass through the perforations in the cathode walls. These bottoms or plugs are made fast in the cathodes by clamping means consisting of bars 75 33 laid against the longer sides of the cathode members, and bolts 34 passing through said bars and having nuts on their ends.

The cathodes are assembled with the anode chamber by passing them through the openings 27 in the lower clamp plate 22, setting up the walls and crossbars 20 of the anode chamber upon the flanges of said cathodes, laying the cover plate or slab 19 of the chamber on top of the walls, and the top 80 clamp plate 21 on the cover, and then making all fast by placing the tie rods 24 in the lugs of the clamp plates and setting up the nuts on said tie rods. A sufficient number of lugs are provided on the clamp plates, as 85 shown in Figures 1 and 6 in the positions required to tie the parts together securely; and the lugs are preferably made with open slots to enable these tie rods to be easily and quickly put in place. The turned over edges 90 of the diaphragms 30, as already indicated, provide packings between the cathodes and the walls of the anode chamber, and in addition there may be other packings between such walls and the clamp plate 22, and also, 95 if needed, between the walls and cover of the anode chamber, to stop leakage of liquid or air at the joints between these parts. And preferably also the contiguous faces on the upper edge of the cathode chamber 11 and 100 the under side of the lower clamp plate are finished accurately, and a packing 35 is there inserted to make a leakage tight joint. But the cathodes come into direct contact with the lower clamp plate 22 and make electrically conducting contact therewith, inasmuch as both this plate and the cathodes are 105 of metal.

The anodes 14 are passed through the openings in the top and bottom clamp plates, 110 and also through openings in the cover 19 of the anode chamber into the interior of the respective cathodes. Such anodes are preferably of carbon made in the form of flat bars. I have designed the cell to take standard forms and sizes of such bars, making the cathodes of such width as to admit two bars arranged side by side, and to provide a clear space on each side of the bars. The latter are supported on the cathode bottoms a sufficient distance above such bottoms to avoid danger of short circuiting by accumulation of conducting matter which may be detached from the carbons or precipitated from the electrolyte and settled upon the bottom 115 120 125 130

plugs. A suitable means for thus supporting the anodes comprises strips 36 and 37 of glass, porcelain, slate, hard rubber, or other insulating material set edgewise upon the 5 bottom pieces both longitudinally and across the same, and conveniently secured in the edgewise upright position by entering properly formed and located grooves in the blocks, as shown in Figures 3 and 4. The 10 anodes are further guided into position and held out of contact with the sides of the anode tubes by guide bars 38, one of which is shown in detail in Figure 5, which occupy the corners of the cathode tube and have 15 channels 39 located to receive the outer corners of the anodes. The inner or adjacent corners of the anodes may be engaged and positioned by spacer bars 40 adapted to be set against the side of the cathode, and having 20 two channels to receive the adjacent corners of the anodes and a rib between such channels projecting between the anodes and holding them apart from one another; but either or all of these guiding and spacing 25 bars may be omitted if desired.

The openings in the cover plate of the anode chamber through which the anodes pass are substantially aligned with the openings of the clamp plates, but are of less dimensions than such openings in order to insure that the anodes will not come in contact with the top clamp plate. When the anodes are in place the openings in the top plate are closed by packing material 41 or a 30 sealing substance of any desired sort in order to prevent entrance of air to the interior of the cell at these points. When renewal of the anodes is required this packing or sealing substance may be readily removed, and 35 thereafter readily replaced or substituted. By means thereof, and of the fluid tight construction of the cell as previously described, it is made possible to operate the cell under vacuum, that is, with its internal 40 pressure less than atmospheric.

It will have been appreciated from the foregoing description that the cathodes are suspended from the anode chamber, that the anodes are supported in the cathode tubes, 50 but the anode chamber and cathode tubes are assembled in a rigid unit construction, and that this construction is not permanently secured to the casing or box 11, nor in this particular construction secured to such box 55 at all. Thus the upper structure can be lifted from the box at any time.

Each cathode with its contained anode forms essentially one cell, but the casing enclosure is constructed to contain within one 60 set of enclosing walls, a number of such cells, which number may be relatively large. Thereby the capacity of the cell is increased without corresponding increase in its bulk and weight. That is, by this invention I 65 have provided a means wherein the effect of

a multiplicity of cells is obtained in a construction which is more compact and less expensive in first cost and maintenance than any possible collection of single cells, each having its individual shell or case 70 and collectively having the same capacity, can possibly be. The design also is such as to give a very large area of electrode surface, with narrow spaces between the complementary anodes and cathodes, whereby the 75 internal efficiency of the cell is made very high. The diaphragms 31 are in effect porous partitions separating the electrolyte, which may also be called the anode liquor, from the product of the electrolysis, which 80 may be called the cathode liquor, in order to prevent recombination of the product with the electrolyte. Such partitions enclose compartments which are in communication with and essential parts of the anode chamber, 85 but are offset in a manner causing them to enter the cathode chamber whereby the above described large area of opposed surfaces of anode and cathode is afforded in a compact structure having relatively small bulk. All 90 of the anodes are contained in the same common anode chamber and severally occupy the said offset or projecting compartments thereof; while such compartments and the cathodes complementary to the several anodes 95 are all contained in the one common cathode chamber.

Without intending thereby to indicate a limitation in the scope for which I claim protection, I may give illustrative dimensions 100 and sizes as follows for a cell embodying this invention which is practically operative in a satisfactory manner. In such cell the box or case has dimensions of $21\frac{1}{2}$ inches long, $18\frac{1}{2}$ inches wide and 22 inches deep, being 105 made of cast iron with walls one-half inch thick and with an inwardly directed flange at its upper edge. The anode chamber has the same length and width and a height of $8\frac{1}{2}$ inches, made of walls which are approximately $1\frac{1}{2}$ inches in thickness; the cathode tubes are 21 inches long with transverse dimensions of $15\frac{1}{2}$ inches by 3 inches, and the flanges on the top edges thereof about $\frac{1}{8}$ inch wide. The clamp plates are $\frac{3}{8}$ of an inch 110 thick, and the anodes 2 inches by 7 inches in transverse dimensions and 30 inches long.

I will now describe the electrical connections by which current is conveyed to and from the anodes and cathodes. Referring 115 to Figures 1, 3, and 4, 43 and 44 represent the main leads or omnibus bars of one cell unit, the bar 43 being laid upon the lugs at one side of the top clamp plate and secured thereto by the upper clamping nuts 25, and the bar 44 supported either by the next cell unit or by other means. Inasmuch as both clamp plates and the tie bars 24 are of iron or steel, or other metal, and are therefore 120 conductors, the bar 43 is thereby put into 125 130

electrical connection with the cathodes. The other bar 44 is connected to all of the anodes of the cell unit in parallel by conductors 45, the latter preferably being flat strips, although they may be of any other character. Each of the conductors 45 is secured to the bar 43 by a clamp bolt 46 passing through slots in these members which cross one another and thereby permit adjustment of the 10 connections either lengthwise or crosswise.

For connecting the conductors with the individual anodes, I have designed a clip which is adapted to permit quick and easy connection to and disconnection from both 15 the anode and the conductor, and the preferred form of which is shown in detail in Figure 8. This clip comprises two pieces 47 and 48 bent or otherwise shaped to form jaws 49, 50 adapted to embrace the conductor, 20 and other jaws 51, 52 on their opposite ends spread more widely apart so as to grip the end of the anode. A bolt 53 is passed through these pieces between their jaw ends and receives a wing nut 54, by turning of 25 which the jaws may be tightened or relaxed. The clip thus is adapted to be easily fitted to conductors and anodes which vary considerably in width, and to be slipped easily on or off from the same. When the conductor is a 30 flat bar of ribbon stock, it is preferably twisted through a quarter turn at some point between the bar 44 and the nearer anode, so that it will lie flatwise against the bar and be presented edgewise toward the anode in 35 order most efficiently to be engaged with the clip.

A modified form of connection is shown in Figures 9 and 10, in which the conductor 45 is laid flat upon the top ends of the 40 anodes and is secured by screws 55 passed through the conductor into threaded holes in the anodes.

Assuming that the bar 44 is connected to the positive terminal of a battery or generator circuit, or of any source of electrical 45 energy, and that the bar 43 is connected to the negative terminal of such circuit, then current passes to all of the anodes in the said unit, and from the latter through the electrolyte to the cathodes, in parallel. But it is not necessary that each unit be connected alone in the electrical circuit, for these units are capable of being coupled in an indefinitely extended series, and the 50 electrical connections above described are adapted particularly for so coupling them. Therefore the bar 43 is extended at one end beyond the casing, and is offset either laterally or vertically, or both laterally and 55 vertically on the diagonal, and is continued on for a distance substantially equal to the bar 44. The part thus extended is adapted to be connected with the anodes of the next cell unit in the series in the same manner 60 that the bar 44 is connected with the anodes

of the cell already described, as shown in Figure 1. The offsetting of the bar in the manner described enables it to pass clear of the negative omnibus bar of the next cell, when the two cells are properly placed. 70 Similarly the bar 44 already described may be considered as a like continuation or extension of the negative bus bar of a cell next preceding in the series, although such cell is not here shown. Thus the invention includes an improved means for connecting the electrodes of the cell in the electrical power circuit, and as a part of such means, an extended bar which is at one end the positive lead for one cell and at the opposite 75 end is the negative lead for a preceding cell. 80

One of the uses for which the cell above described is particularly well adapted is that of making chlorine gas and caustic soda from an aqueous solution of common salt. 85 In this use chlorine collects in the upper part of the anode chamber, from which it is led away by a pipe 56, which may be set in any desired position; while caustic soda is withdrawn from a pipe 57 at the bottom. It 90 is of advantage to operate the cell under vacuum, as thereby the life of the diaphragms within the cathode tubes is largely extended, and when it is so operated, a suitable trap will be provided for receiving 95 the discharge from the pipe 57 and preventing inflow of air. I have not shown any such trap here, since traps satisfactory for the purpose are already available in the open market and I may use any one of a 100 number of such traps. Substantially any steam or vacuum trap which is not dependent upon temperature variations for its operation will serve my purpose here. Nipples 58 through the bottoms of the cathode 105 tubes, and pipes 59 leading therefrom, are provided to carry away outside of the cell any sediment which may collect on such bottoms.

For replenishing the electrolyte I provide a filling tube or supply well 60 which is mounted on the outside of the cell and is provided with a laterally projecting branch 61 which passes through the wall of the anode chamber and is packed or sealed 110 therein. Any suitable means in addition to this branch outlet may be provided if desired for supporting the well. The well is further a gage showing the height of liquid within the cell, and for that purpose it may be of glass or other transparent material to permit viewing of the liquid level directly; and I may use in connection with it a float 62 carrying a visible indicator 63, and in that case the well need not 115 be transparent in any part.

This particular cell having four cathodes or compartments has been designed to carry one thousand amperes of current; but by enlarging the unit and providing more than 130

the number of cathodes here shown, it can be made to run at a greater load up to any reasonable limit desired. As I have already said, the number of cell pairs, (by which I mean the complemental anode and cathode providing the essential parts of a cell) may be greatly enlarged over that here shown within limits fixed only by the allowable weight and bulk of the unit structure.

10 Among the advantages and useful features of the cell embodying the invention hereinbefore described are the following; lower first cost in proportion to capacity, less floor space occupied by units of given capacity, and therefore lower cost for buildings, and lower cost of maintenance, all due to the fact that a number of cell pairs are contained in the same box or case; the fact that the construction permits shipment 15 of the cell from its place of origin all set up and ready to run; long life of the diaphragms due to operation under vacuum; the fact that the cell is self-contained and its construction prevents danger of leakage 20 of its contents; low cost of wiring due to the invention in the electrical connections above described; its strength and rigidity, making it substantially indestructible; its flexibility, due to the fact that the cell can 25 be made to conform to any available current; and its beauty of design.

What I claim and desire to secure by Letters Patent is:

1. An electrolytic cell structure, comprising a unit casing and a plurality of cell pairs contained within said casing, each of said pairs consisting of an anode and a cathode.

2. An electrolytic cell unit comprising a plurality of cell pairs each having an anode 40 and a complemental cathode, and a box or chamber containing electrolyte, and means for supporting said cell pairs in a manner such that they dip into such electrolyte.

3. An electrolytic cell comprising a casing, a cathode formed as a metallic tube supported within said casing and having a bottom, and an anode occupying the interior of said tube and supported by said bottom but insulated from the tube.

4. An electrolytic cell comprising a box forming a cathode chamber, an anode chamber supported on said cathode chamber, a cathode secured to the anode chamber and projecting therefrom into the cathode chamber, said cathode being of tubular form having perforated metal walls and a non-metallic bottom, and an anode supported by said bottom and extending thence through the anode chamber and out from the anode chamber.

5. In an electrolytic cell a metal tube having perforated walls, an insulating bottom within said tube, a pervious insulating lining within the tube, means for supporting said tube by its upper end, and an anode con-

tained in said tube and supported by the bottom thereof, said tube being a cathode in the same circuit with the anode.

6. An electrolytic cell comprising a box forming a cathode chamber, a second box 70 forming an anode chamber superposed upon the first named box and having as its bottom member a plate provided with a number of openings, metal tubular cathodes passing through said openings into the cathode chamber 75 and having flanges at their upper ends bearing upon the plate beside the openings, and anodes located in the interior of the several cathodes, and being connected to the positive side of an electric circuit, of which 80 the negative side is connected to the cathodes.

7. An electrolytic cell unit comprised by a box or cathode chamber, a metal plate having openings supported upon said box and extending over the top of the same, tubular 85 cathodes passing through said openings into the interior of the box and having flanges lying over and resting upon the plate, an anode chamber comprised by walls supported by said plate and intermediate crossbars, 90 said walls and crossbars bearing upon the flanges of the cathodes and securing the latter in place, a second plate overlying the top of said anode chamber, tie members engaged with both plates connecting the latter and 95 the interposed anode chamber in a rigid structure, with the aforesaid cathodes secured thereto, and anodes contained partly in the interior of said cathodes and partly in said anode chamber.

8. An electrolytic cell comprising a hermetically sealed casing, a tubular metal cathode closed at one end and having perforated walls, an anode within the cathode out of contact with the walls thereof, means 105 for admitting electrolyte to the cell, and means for withdrawing electrolyte from the cell, the cathode being arranged with respect to the admission and withdrawal means to cause flow of the electrolyte into its interior through one end and out through the perforations in its walls.

9. An electrolytic cell comprising a case adapted to contain electrolyte and having means in its upper part for admission, and 115 means in its lower part for withdrawal of electrolyte, a tubular cathode having a closed bottom and an open upper end and perforated side walls supported in said casing in its open end below the normal level 120 of electrolyte, and an anode contained within the interior of said cathode out of contact with the walls thereof.

10. In an electrolytic cell a tubular cathode formed of two pieces of sheet metal having 125 their opposite ends bent up to form wings, and being assembled with the wings of one overlapping the wings of the other.

11. In an electrolytic cell, an electrode pair comprising a tubular metallic cathode, 130

a bottom piece secured in one end of said cathode, an insulating support upon and rising from said bottom piece, and an anode within said tubular cathode resting on said support and extending longitudinally through the cathode.

12. In an electrolytic cell, an electrode pair comprising a tubular metallic cathode, a bottom piece secured in one end of said cathode, an insulating support upon and rising from said bottom piece, and an anode within said tubular cathode resting on said support and extending longitudinally through the cathode, and insulating spacers or guides interposed between the anode and the walls of the cathode in positions where they hold the anode out of contact with said walls.

13. An electrolytic cell comprising a casing, a metallic plate interposed transversely between parts of said casing and having a number of openings, tubular cathode members passing through said openings and connected electrically with said plate, an omnibus conductor in electrical connection with said plate, a plurality of anodes each contained in the interior of one of said cathodes and protruding from the top of the casing, a second omnibus bar, and conductors secured to the several protruding anodes and joined to said second bar; in combination with a second cell having corresponding anodes, cathodes, and omnibus bars and on which the bar corresponding to the

aforesaid second omnibus bar is an extension 35 of the first named omnibus bar of the said first cell.

14. An electrolytic cell comprising a box, metal clamp plates on the top and bottom of said box, and having openings, clamping means connected to said top and bottom clamp plates and causing them to grip the box between them, tubular cathodes having flanges gripped between the lower clamp plate and adjacent parts of said box, a lower 45 box on which the said lower clamp plate rests and into which said cathodes project, an omnibus conductor lying upon and secured to the upper clamp plate, and being in electrical connection through the clamp- 50 means and the lower clamp plate with the cathodes, the anodes contained in the interior of the several tubular cathodes and projecting through the first named box above the upper clamp plate, being insulated therefrom and from the cathodes, conductors attached to the several anodes, and a second omnibus conductor to which all of the last-named conductors are secured.

15. A unit anode chamber having a plurality of cell pairs each consisting of a tubular cathode and an anode therein, and a cathode chamber upon which said anode chamber is mounted removably and into which said cell pairs project. 65

In testimony whereof I have affixed my signature.

EDWARD A. ALLEN.
